UNITED STATES PATENT OFFICE

ROY P. M. DAVIS, OF MOUNT UNION, PENNSYLVANIA

BRICKMAKING MACHINE

Application filed June 11, 1929. Serial No. 370,130.

My invention relates to machines for making brick and more particularly to means for placing the molded brick upon the pallets.

Heretofore it has been the practice to fill the mold on a bed plate and then invert or turn the mold over in depositing it upon the pallet. Another method has been to fill the mold with the brick making material or mud while the mold rests upon a plunger and then 10 remove the brick by pushing or lifting the same off the plunger. These methods have proven particularly objectionable when soft mud is used, due to the fact that the mud settles during the tilting or inverting step and 15 where the brick is lifted or pushed from the plunger a large percentage of broken, mishapen and otherwise damaged bricks are produced.

The object of my invention is to overcome 20 the objections mentioned by placing the molded brick upon the pallet before taking the brick out of the mold and without inverting the mold.

Other and further objects and advantages 25 of my invention will be apparent as the specification is considered in connection with the accompanying drawings, in which:

Figure 1 is a side view of the machine partly in section, the mold being shown in 30 full lines in position assumed as it is pushed onto the liner plate and in dotted lines in its advanced or filling position, the pedestal being shown in lowered or inoperative position;

Figure 2 is a view similar to Figure 1, the mold being shown in full lines in filling position and the pedestal being shown in elevated or operative position;

Figure 3 is an end view; and

Figure 4 is a plan view.

Referring more particularly to the drawings wherein like reference numerals refer to corresponding parts throughout the several views, 1 denotes a pair of transversely disposed pallet supporting rails suitably mounted in the main frame of the brick making machine (not shown). Secured to one of the transverse rails 1 is a guide bar 2, and to this bar 2, the bent rear end portion 3 of a cover or liner plate 4 is bolted or otherwise 50 suitably secured, as at 15.

The cover plate is formed from a flat smooth sheet, preferably of tin, of sufficient width to slidably support the brick containing portion of compartments of a conventional mold 5, and of sufficient length to extend from the receiving station A to the filling station B of the machine. Openings 6 of substantial size are formed in the cover plate 4, to permit passage therethrough of excess mud which may escape from the top of the mold. In order to preclude the possibility of either the mold 5 or pallet 7 catching on the edges created by these openings, as the mold and pallet are moved from one station to another, the forward edges 8 are 65 beveled, as illustrated in Figure 4.

For the purpose of facilitating movement of the mold 5 to and from various parts of the brick machine for filling, stripping, cleaning and other operations, not shown, the ends 70 of the mold are notched or beveled, as at 18, to accommodate the reversely beveled rails 9, suitably mounted in the main frame of the brick machine.

In practice the mold is pushed along the 75 tracks 9 by any suitable means, such as pusher arms 20, and on this rail are located a multiple of molds in the various positions required for filling, stripping, slicking etc. Intermittently these molds are advanced forward 80 along the rail, and in the process of advance pallets 7 are introduced on transverse tracks 1 which are on a level immediately below the lower surface of the mold. Lug 10 on the mold, which extends below the lower surface 85 of the mold comes in contact with the pallet as the mold moves forward, and the two will then advance together, the mold above and the pallet beneath the cover plate. The pallet rests upon and is pushed forward along the 90 longitudinally disposed tracks 11.

As the mold and pallet are slid along to the filling station B, they pass the openings 95 6 in the cover plate and come to rest above a reciprocable pedestal 12. This pedestal is then elevated by any suitable mechanism, not shown, from Figure 1 to Figure 2, position, thus tightly clamping the mold, cover plate and pallet together. After the filling operation, the pedestal drops to Figure 1 or inoper- 100

ative position and the mold and pallet are again pushed forward to stripping station C. During this last step, the mold and brick therein slide off the forward end of the cover plate and are deposited directly upon the pallet, where the brick are ejected from the mold by any well known means, not shown.

It will of course be understood that the relative horizontal planes of the mold tracks 9 and the pallet supporting tracks 1 and 11 are such that the bottom of the mold and the top of the pallet will be maintained in substantially the same horizontal plane with the cover or liner plate therebetween.

15 After the mold has been stripped from the brick at C position the mold is returned to A position by any approved means, not shown, and the cycle of operation just described is then repeated indefinitely.

20 Having thus described my invention:

What I claim as my invention is:

1. A brick making machine having a mold supporting means and a pallet supporting means adapted to receive and slidably 25 support the mold and pallet thereon, said mold supporting means and said pallet supporting means also adapted to maintain the bottom of the mold and the top of the pallet in the same substantially horizontal plane, a 30 fixed thin smooth liner sheet adapted to rest beneath the mold and upon the pallet, and means for transferring the mold across the face of the liner sheet directly to said pallet without disturbing the substantially hori- 35 zontal position of the mold.

2. A brick making machine having a mold supporting means and a pallet supporting means, a thin smooth apertured liner plate positioned between the horizontal planes of 40 said surfaces in contact with the bottom of the mold, and means for sliding a mold after the mold has been filled with mud out of contact with the liner plate and into contact with the pallet.

45 3. A brick making machine having a mold supporting means and a pallet supporting means, a thin smooth liner plate and means for supporting the same between the bottom of a mold and the top of a pallet, means for 50 clamping the mold and the liner plate and the pallet together, and means for simultaneously sliding the mold and the pallet out of contact with the liner plate and into contact with each other.

55 4. A brick making machine having a mold supporting means and a pallet supporting means, a thin smooth liner plate between said surfaces, and means for sliding a mold after the mold has been filled with mud on top of 60 the pallet, said liner plate having openings therein adapted to permit the passage there- through of excess brick making material.

65 5. A brick making machine having a mold supporting means and a pallet supporting means, a thin smooth liner plate between said

surfaces, and means for sliding a mold after the mold has been filled with mud on top of the pallet, said liner plate having openings therein adapted to permit the passage there- through of excess brick making material and the marginal forward edges created by said openings being bevelled.

6. A brick making machine comprising a fixed thin smooth liner plate, means for slidably supporting a mold and a pallet in contact respectively with the upper and lower surfaces of said liner plate, and means on said mold for engaging the pallet whereby when said mold is pushed across and beyond the end of said plate and out of contact therewith said pallet will move correspondingly and the mold will be deposited on the pallet.

7. In a brick making machine, a thin smooth liner plate for slidably supporting the brick in a brick mold, said plate having apertures therein for permitting escape there- through of surplus brick making material.

8. In a brick making machine a smooth thin apertured liner plate, a mold above and a pallet below said plate, means for advanc- 90 ing the mold and pallet in registered relation across the aperture in said plate, means for clamping the mold, liner plate and pallet together, before filling the mold, and means for simultaneously sliding the mold and the pallet out of contact with the liner plate and into contact with each other.

In testimony whereof I affix my signature.

ROY P. M. DAVIS.
